UNITED STATES PATENT OFFICE.

ROBERT BEARDSLEY, OF CHICAGO, ILLINOIS.

DESIGN FOR A LAMP.

Application filed March 5, 1928. Serial No. 25,697. Term of patent 3½ years.

To all whom it may concern:

Be it known that I, ROBERT BEARDSLEY, a citizen of the United States, residing at Chicago, in the county of Cook and State of Illinois, have invented a new, original, and ornamental Design for a Lamp, of which the following is a specification, reference being had to the accompanying drawing, forming a part thereof.

In the drawing, Fig. 1 is a plan elevation of a lamp, showing my new design; and

Fig. 2 is a front elevation of the lamp.

I claim:

The ornamental design for a lamp, as shown.

ROBERT BEARDSLEY.
